UNITED STATES PATENT OFFICE.

MATHEW SCHWINDLING, OF WEST NEWTON, PENNSYLVANIA.

TIE-PLATE AND RAIL-ANTICREEPER.

1,160,331.

Specification of Letters Patent. Patented Nov. 16, 1915.

Application filed August 28, 1915. Serial No. 47,858.

To all whom it may concern:

Be it known that I, MATHEW SCHWINDLING, a citizen of the United States, residing at West Newton, in the county of Westmoreland and State of Pennsylvania, have invented certain new and useful Improvements in Tie-Plates and Rail-Anticreepers, of which the following is a specification, reference being had to the accompanying drawings.

My invention relates to means for holding railway rails down upon the ties, and particularly to a combined tie plate and rail anti-creeper.

One object of the invention is to provide means for holding a rail upon a tie, in the nature of a rail chair and tie plate which will prevent the rail from cutting into the tie and hold the rails securely from longitudinal movement.

A further object of the invention is to provide a tie plate and rail anti-creeper which will support the rail very firmly and which, if the rail breaks, will hold the broken ends of the rail securely in alignment with each other.

A further object of the invention is to provide a rail chair or tie plate, so constructed that the rail may be readily attached or detached therefrom without the necessity of driving or pulling spikes, and which will thus eliminate labor in setting rails or replacing them.

Other objects will appear in the course of the following description.

My invention is illustrated in the accompanying drawings, wherein:

Figure 1 is a top plan view of my tie plate and anti-creeper mounted in connection with a rail and tie; Fig. 2 is a top plan view partly in section of the plate and anti-creeper; Fig. 3 is a section on the line 3—3 of Fig. 1; Fig. 4 is a section on the line 4—4 of Fig. 1; Figs. 5 and 6 are under side views of the wedges.

Referring to these drawings, 2 designates generally a tie plate. This comprises a longitudinally extending web 3 having at one end a relatively wide transversely extending head 4 or plate which is adapted to rest upon the tie and at the other end a transversely extending web or plate 5. On

one side or end of the head 4 there is provided the overhanging flange 6 having a downwardly and outwardly inclined inner face adapted to engage over the base flange of the rail A. This thickened portion 7 of the web head 4 is formed with the spike openings 8, preferably two in number. The inner wall of the overhanging flange 6 extends parallel to the rail and parallel to the web 3. The opposite side of the head 4 is formed with the thickened portion 9 to provide the overhanging flange 10, the under face of which flange is parallel to the bottom of the tie plate. The inner wall 11 of this flange extends at an angle to the longitudinal axis of the web 3 and the floor of the web 4 is cut away or grooved as at 12, the wall 13 of this groove being in a slightly divergent relation to the inner wall 11 of the flange. The head 5 is also formed on one side with the thickened portion 14 which is cut away to form an overhanging flange 15 the inner wall of which is parallel to the axis of the web 3. At its opposite end the web 5 has a thickened portion 16 formed to provide an overhanging flange 17, the inner wall 18 of which extends to an angle to the longitudinal axis of the web 3 and this angle is preferably greater than the angle of the inner wall 11 of the flange 10. The web of the head 5 is also grooved or cut away as at 19, the wall 20 of this groove being in slightly divergent relation to the wall 18.

Coacting operatively with the thickened portion or abutment 9 and the thickened portion or abutment 16 are the wedges 21 and 22. The cross sectional form of these wedges is shown in Fig. 3. Each wedge has an inner edge face 23, which, when the wedge is in position, is parallel to the axis of the web 3, this inner edge face being cut away as at 24 to extend over the base flange of the rail and bear against the edge of the base flange. At its outer edge each wedge is formed with the downwardly extending flange 25 which fits between the overhanging flanges 10 or 17 and the floor of the grooves 12 or 19 as the case may be. Each flange 25, as illustrated in Figs. 5 and 6, is slightly wedge-shaped in plan or horizontally and vertically so that when the flange 25 is forced into its seat it will have wedging en-

gagement with the overhanging flange 10 or 17 and be locked in place. Furthermore, of course, the face 26 of each wedge has wedging engagement with the edge of the overhanging flange 10 or 17, respectively.

The thickened portion or abutment 9 is formed with spike holes 8 as previously described for the thickened portion or abutment 7, and by means of spikes 27 driven 10 through these openings the tie plate is held securely down upon the tie beam. After the tie plate is placed upon the tie B the rails are disposed in position and then the wedges 21 are driven home, thus clamping the rail 15 securely in place and bracing it against lateral thrust. The tie plate is so disposed that any tendency of the rail to creep in one direction will cause the wedges to tighten up and thus hold the rails securely against any 20 creeping movement. Furthermore, as in adjusting rails or setting them it is not necessary to spike the rails themselves, it will be obvious that the use of my device will save the work of from fifteen to twenty men. One 25 man can loosen as many rails as twenty men can take out in changing rails, and one man can tighten up as many rails as twenty men can put in. If the rail should break between the tie plate and the anti-creeper, my 30 construction will keep the broken ends of the rails in alinement with each other, and if the rail should break between the anti-creeper and the second tie the anti-creeper will protect it. Furthermore, the ties will be kept 35 straight and the rails will not be allowed to move. If it is not desired to use this device on every tie and it is only necessary to keep the rails from creeping, four or five of these tie plates and anti-creepers may be disposed 40 along the rail and will securely hold the rail from any creeping movement. Ordinarily, however, there will be as many tie plates and anti-creepers as there are ties. The head 4 of the tie plate and the portion 3 45 will rest upon the tie and the head 5 will be disposed between ties.

It is again pointed out that the wedges 21 and 22 not only have wedging engagement between the abutments and the rail but each 50 of these wedges has wedging engagement by means of the flange 25 with the abutment 9 or the abutment 16. This is necessary because thereby the wedges are held more securely from accidentally coming out of place. 55 My device may be used on three kinds of rails, 70 pounds, 80 pounds, and 100 pounds, without change. It will be noted that the angle of the wedge 21 is greater than the angle of the wedge 22. Thus the wedge 21 60 acts quicker and with more power than the wedge 22. The wedge 22 on the tie plate acts primarily as a means for holding the rail to the tie while the wedge 21 acts primarily as a means for keeping the rail from

creeping. The greater the angle of the 65 wedging face of the wedge 21 the greater will be the wedging action with the same amount of longitudinal movement.

Having thus described my invention, what I claim is:

1. A device of the character described, comprising a longitudinally extending web having laterally extending heads at opposite ends, flanges on one end of each head adapted to overhang and engage with the base 75 flange of a rail, overhanging flanges on opposite ends of the heads, and rail engaging wedges having interlocking engagement with the overhanging flanges and movable in one direction to clamp the rails in place. 80

2. A device of the character described comprising a tie plate having means for attachment to a tie, a web extending longitudinally from the tie plate and having a head, means on the tie plate for engaging a rail 85 and holding the rail to the tie plate and the web, and means on the head for engaging the base of a rail and locking it in place.

3. A device of the character described comprising a longitudinally extending web having laterally extending heads at opposite ends, a flange on one end of each head cut away to overhang and engage with the base of a rail, abutments on the opposite ends of the heads formed to provide overhanging 95 flanges, the inner walls of said abutments and the inner edges of the flanges extending at an angle to the longitudinal axis of the web, and rail engaging wedges adapted to engage beneath said flanges and having 100 wedging engagement with the inner walls of said abutments.

4. A device of the character described comprising a tie plate having thickened abutments at its ends, one of said abutments being formed with an overhanging rail engaging flange, the other being provided with an overhanging flange, both of said abutments being formed with spike openings, a web extending longitudinally from said tie plate, 110 a head formed upon the end of the web and having lateral abutments each formed with an overhanging flange, and rail engaging wedges having interlocking engagement with both of said abutments.

5. A device of the character described comprising a longitudinally extending web having laterally extending heads at opposite ends, each of said heads being formed on one side with an overhanging flange adapted to engage the base of a rail, each of said heads at its opposite end being formed with an abutment having an overhanging flange, the inner face of each abutment and the edge of the flange being inclined relative to 120 the axis of the web, the face of the head immediately beneath the overhanging flange being longitudinally grooved, and rail en-

gaging wedges cut away to fit over and engage with the base flange of a rail, each of said wedges having on its lateral edge a flange adapted to wedgingly engage in said 5 groove against the inner face of the abutment and beneath the overhanging flange thereof.

In testimony whereof I hereunto affix my signature in the presence of two witnesses.

MATHEW SCHWINDLING.
